COMBINATION SCREW DRIVER AND PLIERS

Filed Nov. 29, 1929

INVENTOR.

Alfred F. Mueller
BY

Frank G. Barnes.

ATTORNEY.

UNITED STATES PATENT OFFICE

ALFRED F. MUELLER, OF BAY CITY, MICHIGAN

COMBINATION SCREW DRIVER AND PLIERS

Application filed November 29, 1929. Serial No. 410,352.

This invention relates to a compound tool of the handle lever type, particularly designed for removing round slotted head screws or stove bolts and the like from wood, metal or sheet metal, such as for instance, automobile running boards, and which can also be used as conventional pliers for holding or cutting when so desired.

The prime object of the invention is to design a compound tool comprising a screw driver and plier, and with which slotted and round head stove bolts and screws can be readily removed.

Another object is to design a compound tool provided with sharp jaws which grip the head of the screw when the screw driver blade engages the slot in the head, eliminating the possibility of chipping and breaking the side walls of the slot.

A further object is to provide a simple, substantial, and convenient compound tool, which can be readily manufactured and assembled, and which is easy and handy to use.

A further object still is to provide adjustable means for holding the screw driver blade firmly in the slot in the screw head.

With the above and other objects in view, the present invention consists in the combination and arrangement of parts, herein-
so after more fully described, illustrated in the accompanying drawing, and particularly pointed out in the appended claims, it being understood that changes may be made in the form, size, proportion, and minor details of construction, without departing from the spirit, or sacrificing any of the advantages of the invention.

In the drawing.

Fig. 1 is an edge view of my improved compound tool the dotted lines showing the cam lever in raised position.

Fig. 2 is a plan view, the dotted lines illustrating the pliers in open position.

Fig. 3 is a detail side view of the slot engaging blade.

Fig. 4 is a sectional end view taken on the line 4-4 of Fig. 3.

Fig. 5 is a fragmentary edge view showing the tool in position for removing a stove bolt.

In the removal of stove bolts and screws which are rusted in place, with a conventional screw driver, the side walls of the slot in the head chip and break, so that slot is destroyed, and the head must then be chiseled off, and I have therefore perfected a very simple compound tool by means of which the bolts can be readily removed without the necessity of chiseling.

Referring now particularly to the drawing, my improved tool comprises a pair of handle members 6 and 7 respectively, pivotally connected together by means of the pivot pin 8, the lower end which extends through these handles being reduced and shouldered, and the handle 6 is counter-bored as shown at 9 so that the end of the pivot pin may be headed over as at 10 to provide a smooth flat bottom surface.

The front ends of the handles terminate in jaws 11 and 12 respectively, the outer edge of each jaw being rounded as shown, the bottom surface being also slightly rounded in both a transverse and longitudinal plane, so that the ends will be pointed, the inner gripping edge 13 of each jaw being chamfered and beveled so that a sharp edge is provided.

The pivot pin 8 projects above the top of the handles, and is formed with a centrally disposed slot 14 in which a screw driver blade 15 is mounted, the front end 16 projecting downwardly and is wedge shaped, similar to the blade of a conventional screw driver, the opposite end having a short downwardly projecting leg 17, and a pin 18 serves as a stop to limit longitudinal movement of the blade in the slot.

A cam lever 19 is pivotally mounted in the slot by means of the pin 20, and this lever is designed to hold the blade firmly in the slotted head of the stove bolt 21, and when in position as shown in full lines in Fig. 1 of the drawing, this blade can be raised a limited distance as indicated by the dotted lines, but when the tool is in use, the thumb of the operator engages the thumb rest 22 of the lever to hold it firmly in position. A spring 23 is anchored to the lever

and to the handle member 7 and tends to hold the lever down.

In practice the plier handles are spread as shown by dotted lines in Fig. 2, the screw driver blade is inserted in the slot in the bolt head, the handles are then forced towards each other, and the knife edges of the jaws firmly grip the bolt head, the thumb is placed on the lever thumb rest, the tool 10 turned clock wise, and the bolt or screw can be easily removed without destroying the slot, making it unnecessary to chisel off the head of the bolt, or use other means for its removal.

15 From the foregoing description, it will be obvious that I have perfected a very simple, handy and substantial compound tool for removing stove bolts and round headed screws having slotted heads.

20 What I claim is:—

1. A compound tool of the class described, comprising a pair of pliers having beveled gripping jaws, a slotted pivot pin projecting above the pliers, a longitudinally disposed 25 screw driver blade mounted in said slot and means for holding said blade in position.

2. A compound tool of the class described, comprising a pair of pliers having sharp edged gripping jaws, a slotted pivot pin 30 projecting above the face of said plier, an adjustable screw driver blade mounted on said pivot pin, and means for holding said blade in adjusted position.

3. A compound tool of the class described, 35 comprising a pair of handles having slightly rounded sharp edged gripping jaws, a pivot pin connecting said handles and projecting above the face thereof, a screw driver blade mounted on said pivot pin with its end extending between said jaws, and means for holding said blade in set position.

4. A compound tool of the class described, 45 comprising similar handle members having jaws formed with sharp gripping edges, a slotted pivot pin connecting said handles and projecting above the same, a longitudinally disposed member loosely mounted in said slot, the front end projecting downwardly and being sharpened to form a blade, and 50 a cam mounted on said pin for holding said longitudinally disposed member in set position.

In testimony whereof I hereunto affix my signature.

55 ALFRED F. MUELLER.
